United States Patent Office.

THOMAS B. WICKHAM, OF GRANVILLE, OHIO.

Letters Patent No. 77,942, dated May 12, 1868.

IMPROVEMENT IN PORTABLE FENCE.

The Schedule referred to in these Letters Patent and making part of the same.

TO ALL WHOM IT MAY CONCERN:

Be it known that I, THOMAS B. WICKHAM, of Granville, county of Licking, and State of Ohio, have invented a new and useful Improvement in a Portable Fence; and I do hereby declare that the following is a full, clear, and exact description of the construction of the same, reference being had to the annexed drawings, making a part of this specification, in which—

Figure 1 is a perspective view of the fence in position.

Figure 2 is the double brace which binds the sections, by firmly clamping first and second boards at top, and also forming a substantial brace on either side, which are fastened to stakes firmly driven in the ground.

Figure 3 is the combination-lock, which, being fastened at the bottom of the braces, and compressing them, so as to firmly secure the fence at the top, also firmly holds the sections at the bottom.

The nature of my invention consists in constructing each section and brace so as to form a combination-lock and double brace.

To enable others to make and use my invention, I proceed to describe its construction and operation.

I construct each section of such number and width of boards as to form a desirable height, with a projection of three or four inches at each end, so as to form a lap at the joint of the sections. The double brace, marked B B, with notches at top, marked e e, forms a double slot and clamp, marked f f, for the first and second boards at top. The foot of each brace is attached, by any convenient fastening, to stakes marked D D, so as to secure permanence to each panel, in combination with lock marked C C, (with a slot in the centre, marked g,) which extends and is attached to the foot of each brace, and so compresses them as to firmly secure the fence at top and bottom.

What I claim as my invention, and desire to secure by Letters Patent, is—

The manner of locking and supporting the panels by the double brace and clamp B B, in combination with the stakes D D and lock C C, all substantially arranged as set forth in the foregoing specifications.

THOS. B. WICKHAM.
